UNITED STATES PATENT OFFICE.

STEPHEN FAITH, OF CHICAGO, ILLINOIS, ASSIGNOR TO FAITH MANUFACTURING COMPANY, OF CHICAGO, ILLINOIS, A CORPORATION OF ILLINOIS.

DESIGN FOR AN AUTOMOBILE RADIATOR CAP.

Application filed October 2, 1926. Serial No. 19,222. Term of patent 7 years.

To all whom it may concern:

Be it known that I, STEPHEN FAITH, a citizen of the United States, residing at Chicago, in the county of Cook and State of Illinois, have invented a new, original, and ornamental Design for Automobile Radiator Caps, of which the following is a specification, reference being had to the accompanying sheet of drawings, forming part thereof.

In these drawings:

Fig. 1 is a top plan view of my design;
Fig. 2 is a front elevational view; and
Fig. 3 is an end view.

I claim:

The ornamental design for an automobile radiator cap, as shown.

STEPHEN FAITH.
